POLARIZED RELAY.

1,030,811.

Specification of Letters Patent. Patented June 25, 1912.

Application filed May 6, 1911. Serial No. 625,490.

To all whom it may concern:

Be it known that I, WILLIAM S. HENRY, a citizen of the United States, and resident of the city of Rochester, in the county of Monroe and State of New York, have invented a new and useful Polarized Relay, of which the following is a specification.

This invention relates to a relay having a permanently polarized armature.

10 Polarized relays of the type to which this invention relates, are often used in connection with systems, the proper operation of which determines the safety of human beings, for which reason absolute certainty of 15 action must be attained. At the same time the device must not be so susceptible to slight jars and shocks as to be continually moving to the abnormal position, thus creating great annoyance and loss of time.

20 The primary object of the invention is, therefore, to so arrange the magnetic circuits in a polarized relay that a desired movement is certain to occur.

A further object of the invention is to 25 construct a relay of the character described in which an air gap will exist between the armature in normal position and an electromagnet to the pole of which it will be attracted when an abnormal current flows.

30 A further object of the invention is to so construct a relay of the character described, that if the permanent magnet loses its permanent magnetism, current of any 35 polarity flowing in the electromagnet will cause the armature of the relay to assume the abnormal position and open the relay contacts.

The invention consists in the idea of 40 means, a practical embodiment of which is herein illustrated.

In describing in detail the form selected 45 to illustrate the invention, reference will be had to the accompanying drawings, in which like characters of reference designate like parts, and in which:

Figure 1, is a side elevation of one form 50 of my invention. Fig. 2, is a plan view of the form shown in Fig. 1.

Construction.—1, designates a piece of 55 magnet steel bent into the form of a U, properly hardened and permanently magnetized in such a manner that end N becomes the north-pole and end S becomes a south-pole; 2, designates a soft iron member which is fastened to the end S of

member 1, by means of bolt 3, the bolt having a nut 4 thereon which, when screwed up, binds members 1 and 2 firmly together so that they make good magnetic contact, the bolt 3 being of such length that it may 60 be passed through a supporting wall, so that the whole device can be supported on a wall by screwing the nut 5 up tightly on the bolt on the opposite side of the wall from that upon which the relay is, a pin 65 6 being attached to member 2 and being adapted to fit in a suitable hole in the wall to prevent the relay from turning about the bolt 3 as a pivot.

The member 2 has a downwardly extending 70 lug 2¹ which has a hole therethrough in which is inserted the reduced screw threaded end of a cylindrical piece of soft iron 7, there being a nut 8 screwed upon the reduced end of the cylindrical piece on 75 the opposite side of the lug 2¹ from that on which the shoulder formed by reducing the end lies, so that by screwing up the nut, the cylindrical piece 7 is firmly held to the lug 2¹. The opposite end of member 7 80 is also reduced in diameter and bears the enlarged soft iron pole piece 9, forced into place thereon.

Upon the core 7 is placed the coil of wire 85 10, the two terminals of which are designated by 10¹ and 10².

Upon the end N of member 1, is the pivot bearing member 11, fastened thereto by means of the bolt 13 and nuts 14 and 15, the pivot pin being designated by 16, and having an armature 17 mounted thereon for oscillation, one end of the armature extending sufficiently to the right of the pivot pin as viewed in Fig. 1, so that it may be oscillated manually, the other end of the armature bearing a good contact material 18 fastened thereto by a rivet 19, and when in the position shown in Fig. 1, bearing against contact spring 20, the contact spring 20 being held on a block of insulating material 21, by 100 means of binding post 22. The insulating block is fastened to member 2 by means of the projection 2² and the binding post 23, the binding post 23 making good electrical contact with projection 2², and the armature 17 making good electrical contact with pivot pin 16, which is in good electrical contact with member 11, the member 11 being in good electrical contact with member 1, which is in good electrical contact with member 2. 110

In the end 2³ of extension 2, is the non-magnetic pin 24, which being in good electrical contact with the contact material 18 and binding post 23, also forms part of a short 5 path for electrical current from binding post 22, and spring 20, to binding post 23.

Operation.—Terminals 10¹ and 10² may be connected to a source of intermittent and reversible current so that at times there will 10 be no current flowing in coil 10, at other times a current will be flowing in what will be called the normal direction, while at other times a current may flow in coil 10 in what may be called the abnormal or reverse 15 direction. When no current is flowing in the coil 10, the armature 17 will remain in contact with the end 2³ of member 2, or in contact with pole piece 9, with no tendency 20 to move in either direction, that is, it is equally attracted by both the end 2³ of member 2 and by the pole piece 9, so that if placed in contact with either one of these 25 members, it will remain in the moved position. This action of the armature is due to the fact that the end N of member 1 is a north-pole and, consequently, the end 2³ of member 2 is a south-pole, and at the same 30 time the pole piece 9 is also a south-pole; both of these latter being caused to have such polarity by reason of the influence of the permanent magnet 1, so that the flux from the north-pole of the permanent magnet is divided and flows to the pole piece 9 and to the end 2³ of the member 2, so that 35 under normal conditions the end of armature 17 bearing the contact material 18 plays between two poles of like polarity, therefore, it would not have a bias to one more than to the other and if placed in contact 40 with one, would remain in contact.

If current is caused to flow through the coil 10, in what I have termed the normal direction, the polarity of the end N of permanent magnet 1 will remain the same, 45 which, as before, will cause the end 2³ of member 2 to be a south-pole but the pole piece 9, due to the particular direction of the flow of current in the coil 10, will become a north-pole and being connected with member 2, will assist permanent magnet 1 to cause the end 2³ of member 2 to become a south-pole, so that under such 50 conditions there will be a north-pole at the end N of member 1, a north-pole at pole piece 9, and a south-pole at the end 2³ of member 2, due to the combined action of the permanent magnet and current flowing in the coil 10, so that the flux tends to flow from both end N of member 1 and pole 55 piece 9 to the end 2³ of member 2, thus tending to hold the armature 17 against the end 2³ of member 2 causing the contact material 18 to make good contact with contact spring 20, and so decreases the liability of the armature 17 being accidentally moved by a

slight blow or jar. If current is caused to flow through the coil 10, in what I will call the abnormal or reverse direction as it flows in a direction contrary to what it does when flowing in the normal direction, the end N 70 of permanent magnet 1, will remain a north-pole and the pole-piece 9 will become a south-pole, so that the end 2³ of member 2 will be acted upon by two contrary forces one exerted by the permanent magnet 1 tending to make end 2³ a south-pole, another, exerted by the magnetic flux caused by the flow of current in coil 10, tending to make it a north-pole, but as the magnetic flux caused by coil 10, has the stronger effect 80 upon member 2 than that caused by the permanent magnet 1, the end 2³ of member 2 will become a north-pole and, consequently, will tend to repel the armature 17 if in contact therewith, as the armature 17 would by 85 influence of the end N of permanent magnet 1, have a like polarity, and at the same time an exceedingly strong pull would be exerted by pole piece 9, as it is of south-polarity, to pull armature 17 toward it, so 90 that under such conditions the armature 17 would be pulled into contact with pole piece 9, thus breaking the contact between spring 20 and contact material 18. It is to be observed that the stronger the magnetic flux, 95 caused by coil 10, the greater the pull upon armature 18 and the greater the repulsion toward armature 18 exerted by the end 2³ by member 2, and these facts should be carefully borne in mind for therein lies to a large 100 extent the great value of this form of the invention, for in devices of this character heretofore invented and designed to actuate an armature in the manner which has heretofore been described in this specification, 105 the great difficulty has been that when an abnormal current of exceedingly great value flowed through the coil or coils of the device, the armature being at that time in contact with a pole directly acted upon by the 110 flux generated by current flowing in the coils of the devices, a local action was set up which held the armature in the position in which it then was, whereas it should have repelled it, this being due to the fact that 115 the local flux was so much stronger than the flux generated by the permanent magnet that it virtually excluded the flux from the permanent magnet and the device acted as though it were simply an electromagnet with 120 a soft iron armature of neutral polarity. In this device, however, the pole which will have the greatest tractive effect when an abnormal current flows through the coil of the device, is the pole with which the armature is when in normal position, not in contact, so that the greater the amount of abnormal current the greater will be the tendency for the armature to move. It is further to be observed that when an abnormal 130

current flows through the coil of the device, the magnetic flux generated by said current flows in the same direction as the magnetic flux of the permanent magnet, thus tending 5 to increase the effect of said permanent magnet in transmitting to the movable armature a like polarity as the end to which it is pivoted, thus by creating a stronger unlike pole in the armature to that of the pole to 10 which it should be attracted under such conditions; to-wit: the pole piece 9, greatly increasing the efficiency of the device. This method of operation also differs from the polarized relays of the prior art, as heretofore, the flux caused by the electromagnet has, when abnormal current was flowing in the electromagnet, been opposed to the flux caused by the permanent magnet. It is also 15 to be observed that a large air gap occurs in the path of greatest flux with abnormal current flowing, and as the armature is lightly pivoted and is the only movable iron member in the device capable of bridging this air gap, it will most certainly do so; 20 whereas, in other devices of this type in the prior art, the movement of the armature due to abnormal current does not cause the closing of an air gap in the path of the greatest flux, they do not, therefore, have the certainty of action inherent in applicant's construction.

All relays heretofore constructed employing a permanent magnet, and which depend for their proper operation upon the presence 35 of magnetic flux in the permanent magnet are subject to the disadvantage that a body of steel will, in time, lose its magnetism, especially when constantly subjected to a magnetic flux contrary in direction to that 40 of the permanent magnetism of the steel, and when the permanent magnet has lost its magnetism, the relay will not operate as intended when a reverse current flows. In relays upon the operation of which the 45 safety of human lives depend such a possibility should be eliminated, but heretofore no means have been devised to overcome such objection. In applicant's relay such a contingency has been foreseen and fully provided against for if the permanent magnet loses its magnetism the relay contact will then always open when current flows through its coil regardless of the direction of flow, so that the fact that a magnet has 55 lost its magnetism is instantly made known, by the impossibility of closing the contact of the relay when current is flowing in either direction in the coil of the relay, it is furthermore to be observed that the opening of 60 the relay contact is the safe condition and not the dangerous condition, that is, the relay fails on the safe side.

By so constructing the relay that the armature is normally held in a position from 65 which gravity tends to move it, the force

required to move it to abnormal position may be lessened by that amount thus rendering the relay more sensitive than devices heretofore constructed, and by having the armature tension a spring such as 20 in 70 the normal position, if the permanent magnetism of the permanent magnet is lost, the spring 20 will force the armature away from the upper pole with which it is in contact and it will then fall to the lower pole, 75 thus breaking the relay contact, thus also causing the relay to fall on the safe side. In applicant's device it will also be seen that the desired result is accomplished by the use of but one coil, whereas in all devices heretofore constructed of this nature, it has been necessary to employ two coils of wire, and herein applicant has made a decided advance over the prior art.

Having now illustrated one form of mechanism embodying the principle of the invention, and having described the same, what I desire to secure by Letters Patent, and what I claim as new is:

1. In a polarized relay, a permanent magnet approximating the form of the letter U, a soft iron extension bolted to one leg of the permanent magnet, and extending in the plane of the magnet nearly to the other leg of the magnet, a downwardly extending lug 90 on the soft iron extension in proximity to that end fastened to the permanent magnet, a hole therethrough, a soft iron rod having a reduced screw threaded end passing through said hole and clamped thereto by 100 means of a nut screwed upon said reduced screw threaded end, and extending nearly to the far leg of the U magnet and in the plane thereof, and enlarged pole piece of soft iron affixed to a reduced portion of the 105 other end of said rod, a coil of wire wound about said rod in such a direction that normal current flowing therethrough causes said pole piece to be of the same polarity as the adjacent leg of the U magnet, and abnormal current causes it to be of the opposite polarity, a pivot support fastened to the free leg of the U magnet, an armature supported by said pivot approximately midway 110 of its length, one end extending between the pole piece on the said rod and the near end of the U magnet extension piece, the other end extending outwardly from the leg of the U magnet, the said inner end bearing a contact strip, a spring contact adapted to 115 bear against said contact strip when said armature bears against said soft iron extension piece, an insulating block borne by the end of said soft iron extension supporting said contact spring, a binding post passing through said insulating block and through said soft iron extension, and a binding post 120 passing through said insulating block and said contact spring, out of contact with said soft iron extension piece.

2. In a relay, a permanent magnet, an electromagnet and a movable armature, a flow of current in said electromagnet in a normal direction assisting said permanent magnet to hold said armature in one position, a flow of current in said electromagnet in a reverse direction causing in conjunction with said permanent magnet said armature to assume another position, either of 10 said currents in said electromagnet causing said armature to assume said other position if said permanent magnet loses its permanent magnetism, said permanent magnet causing said armature to remain in said 15 other position when moved thereto and contacts controlled by said armature, adapted to move said armature from the first mentioned position if said permanent magnet loses its permanent magnetism.
- 20 3. In a polarized relay, a U shaped permanent magnet, an iron core attached to one limb of the permanent magnet and terminating adjacent the other limb of the permanent magnet having a metallic wire 25 wound thereon, an iron member fastened to the first mentioned limb and terminating just above the end of the said iron core adjacent the other limb, an iron armature pivoted to the said other limb of the permanent magnet oscillatable between the two iron members and held against said contact by the force of the permanent magnetism of said magnet, said contact adapted to force said armature from contacting position when said permanent magnet loses its permanent magnetism, a flow of electricity through said wire in one direction breaking said connection between said contact and said armature, a flow of electricity in the other direction through said wire assisting to maintain said connection.
- 40 4. In a polarized relay, a U shaped permanent magnet, an iron core attached to one limb of the permanent magnet and termi-

nating adjacent the other limb of the permanent magnet having a metallic wire wound thereon, an iron member fastened to the first mentioned limb and terminating just above the end of the said iron core adjacent the other limb, an iron armature pivoted to the said other limb of the permanent magnet and oscillatable between the end of the said iron core and the end of the said iron member, means for manually placing said armature in contact with either said iron core or said iron member, the magnetic force of said magnet holding said armature in the moved position, resilient contacting means engaged by said armature when resting against the end of said iron member adapted to force said armature away from contacting position when said permanent magnet loses its permanent magnetism.

5. In a polarized relay, a U shaped permanent magnet having two iron members attached to one limb, both terminating adjacent the other limb of the permanent magnet, a metallic wire wound on one of said iron members, a contact, an iron armature pivoted on the other limb of the permanent magnet oscillatable between the two iron members and held against said contact by the force of the permanent magnetism of said magnet, said contact adapted to force said armature from contacting position when said permanent magnet loses its permanent magnetism, a flow of electricity through said wire in one direction breaking said connection between said contact and said armature, a flow of electricity in the other direction through said wire assisting to maintain said connection.

WILLIAM S. HENRY.
